UNITED STATES PATENT OFFICE.

GUSTAF E. KRANTZ AND CARL A. KRANTZ, OF CHICAGO, ILLINOIS, ASSIGNEES OF
ONE-FOURTH TO J. H. JOCHUM, JR., OF CHICAGO, ILLINOIS.

SPOTLIGHT.

Application filed March 12, 1923. Serial No. 624,369.

To all whom it may concern:

Be it known that we, GUSTAF E. KRANTZ and CARL A. KRANTZ, citizens of the United States, residing at Chicago, in the county of Cook and State of Illinois, have invented certain new and useful Improvements in Spotlights, of which the following is a specification.

This invention relates to improvements in spot lights, and one of the objects of the same is to provide an improved spot light particularly adapted though not necessarily limited in its use for attachment to the wind shield or screen of an automobile, the light being disposed on one side of the shield and shifting mechanism therefor being arranged on the other side of the screen, the light and operating mechanism therefor being connected through the shield or screen, the whole being supported by the shield at a point within the confines of the edges of the shield.

A further object is to provide an improved light of this character, which is adapted to stand in close proximity to the face of the shield or screen and to be shifted at will from any of its positions to a position at an angle of substantially 90° thereto, thereby enabling the driver to turn the light so as to inspect objects or numbers of residences, the fronts of which residences are parallel with the line of travel of the vehicle.

A further object is to provide an improved light of this character adapted to be readily installed or mounted upon any wind shield.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a front elevation of the spot light showing the same as mounted upon a wind shield and also showing the light in dotted lines in another position.

Figure 2 is a horizontal, sectional view taken on line 2—2, Figure 1, showing the light in full lines in one position and in dotted lines in another position.

Figure 3 is a vertical, sectional view taken on line 3—3, Figure 1.

Figure 4 is a detail sectional view taken on line 4—4, Figure 1.

Figure 5 is an elevation of a detail.

Figure 6 is an end elevation of Figure 5.

Referring more particularly to the drawings, the numeral 10 designates the wind shield of an automobile, which is usually constructed of glass and the shield is provided with an opening 11 therethrough at any desired or convenient position.

The light casing designated generally by 12 the reference numeral 12 may be of any desired or suitable configuration and construction in any suitable manner and is mounted upon an operating arm or lever 13, the extremity 14 of which is preferably shaped to form a handle.

The arm or member 13 is preferably provided midway of its length with laterally projecting lugs or trunnions 15 adapted to be seated in seats 16 in co-operating members 17, the latter being provided with openings 18 therethrough. These members 17 are arranged on opposite sides of the trunnions 15 and are of any desired size and configuration and constructed of any suitable material preferably metal, their diameters being somewhat less than the diameter of the opening 11 in the shield 10.

The seats 16 are preferably of a depth somewhat less than one-half the diameter of the trunnions 15 so that when the members 17 are assembled they will be spaced from each other for a considerable distance as shown more clearly in Figure 3. When the members 17 are assembled the arm or lever 13 will project through the registering openings 18 and the members 17 may be secured together by suitable fastening devices 20, such as screws or the like. One of these fastening devices 20 is preferably provided with a knurled head 21 on one extremity on one side of one of the members 17 and is threaded into a nut 22 on the other side of one of the members 17.

It is obvious that with this construction, the members 17 may be forced toward each other by the adjustment of the screw 20 so as to cause a greater amount of friction to be exerted by the walls of the seats 16 upon the trunnions 15 and thereby clamp the lever 13 against pivotal movement with respect to the members 17, so as to hold the lamp 12 in its adjusted position about its

2
pivot. By loosening the screw 20 the friction will be relieved and the lamp may be swung readily about its pivot.

The nut 22 is adapted to be held against 5 rotation to permit adjustment of the screw 20, in a manner as will be hereinafter set forth.

The members 17 are adapted, when the 10 lamp is secured in position to stand within the opening 11 in the shield 10 and are preferably so arranged that they will stand within the planes of the faces of the screen.

Annular clamping members 23 are disposed 15 on opposite sides of the shield 10 and the openings 24 in the annular members are of a diameter considerably less than the diameter of the opening 11 in the shield 10 and also less than the external diameter of 20 the members 17, so that when the clamping members 23 are placed in position they will engage the screen or shield 10 and also the lateral faces of the members 17.

The clamping member 23 are adapted to 25 be secured in position in any suitable manner such as by means of fastening devices 25 in the form of screws or the like which pass through the opening 11 and engage each other so that when the screws 25 and 30 nuts thereon are tightened the clamping plates 23 will securely hold the members 17 in position to support the light 12.

If desired annular washer members 26, of 35 any desired material, such as fibre or the like may be disposed between the clamping members 23 and the proximate faces of the shield 10 and these washer members 16 are adapted to rest against the proximate faces of the members 17 to form frictional contact therebetween and thereby frictionally 40 control the rotation of the members 17 within the opening 11.

If desired the members 17 may be split 45 as at 27 and deflected as at 28 to form yielding friction surfaces contacting with the washer members 16.

The nut 22 is preferably provided with a 50 flattened surface 28^a as shown more clearly in Figure 1, and this flattened surface engages the inner periphery 29 of one of the members 23, so that the nut 22 will be held 55 against rotation when the screw 20 is adjusted and at the same time the nut 22 will not interfere with the rotation of the members 17 within the opening 11 of the screen 10.

The lever or member 13 is preferably provided with a passage 30 therein, within 60 which the conductor 31 which is connected with the lamp 32, is adapted to be located for the protection of the former. As a means for controlling the light 32 a suitable switch 33 may be provided, which is located in any convenient position for the operator 65 preferably upon the handle end 14 of the

lever 13 and in a position so that when the operator grasps the handle 14 he may manipulate the switch 33 with the thumb of the hand which grasps the handle.

The lever 13 is so shaped and the trunnions 15 are so arranged that when the lamp is in the position shown in Figures 1 and 3, it will stand in close proximity to the shield 10 and by loosening the screw 20 the lamp may be swung by means of the handle 75 14 about its points of pivotal connection with the members 17 and by adjusting the screw 20 the lamp may be clamped in its adjusted position.

When the parts are in this position the 80 operator may bodily rotate the lamp 12 by means of the handle 14 so as to rotate the members 17 within the opening 11, thereby permitting the operator to move the lamp 12 from the position shown in full lines in Figure 1 to the position shown in dotted lines in the same figure or to any intermediate position, and to either side of the pivot. When the lamp has assumed the position shown in dotted lines in Figure 1 90 and in full lines in Figure 2, the operator may then swing the lamp about its pivot from the full line position in Figure 2 to the dotted line position or for a distance of substantially 90°, thereby permitting the 95 operator to inspect objects or numbers of residences, the fronts of which residences are arranged parallel with the line of travel of the vehicle.

It will be manifest that with this construction the lamp is adapted for a universal movement and can be switched or moved to any desired position by the operator and from the side of the shield opposite to the side on which the lamp is located.

It will also be manifest that this improved lamp and support therefor may be readily and quickly applied to any wind shield now on the market and when so applied the device will be compact and the lamp may be moved so that it will stand in close proximity to the shield.

While the preferred form of the invention has been herein shown and described it is to be understood that various changes may be 115 made in the details of construction and in the combination and arrangement of the several parts, within the scope of the claims, without departing from the spirit of this invention.

What is claimed as new is:—

1. In combination, a fixed support having an opening therethrough, a rotatable support in said opening, a spot light on one side of the fixed support, and means mounting the spot light upon the rotatable support for movement therewith and with respect thereto, the said means embodying a lever like member extending through the rotatable support, one end of the lever being 125 130

connected with the light and shaped to assume a position in close proximity to and in a plane substantially parallel with the adjacent face of the fixed support, the other 5 end of the lever being shaped to form a handle on the other side of the fixed support.

2. In combination, a fixed support having an opening therethrough, a bearing member 10 rotatable in the opening, a lever like member, laterally projecting trunnions on the lever and journaled upon the said rotatable bearing member, one end of the lever like member extending beyond the said bearing member 15 and forming a handle on one side of the said support, the other end of the lever like member extending to the other side of the support and shaped to assume a position in close proximity to and in a plane substantially parallel with the adjacent face of the support, and a spot light connected with the last recited end of the lever like member 20 against movement with respect thereto and in a manner that the longitudinal axis of the light will be transverse to the length of the lever like member.

3. In combination, a fixed support having an opening therethrough, a bearing member 25 rotatable in the opening, a lever like member, laterally projecting trunnions on the lever and journaled upon the said rotatable bearing member, one end of the lever like member extending beyond the said bearing member 30 and forming a handle on one side of the said support, the other end of the lever like member extending to the other side of the support and shaped to assume a position in close proximity to and in a plane substantially parallel with the adjacent face 35 of the support, and a spot light connected with the last recited end of the lever like member, and at a substantially right angle thereto.

4. In combination, a fixed support having 40 an opening therethrough, a bearing member rotatable in the opening and substantially within the plane of the faces of the support, annular members engaging the faces of the support and the respective faces of the said 45 member for holding the member in position, a lever like member passing through the said bearing member and journaled intermediate its end to the bearing member, one end of the lever like member forming a handle on one side of the said support, the portion of the lever like member on the other side of the support being shaped to assume a position in close proximity to and in a plane substantially parallel with the adjacent face of the 50 support, and a spot light carried by the last said end of the lever like member and at a substantially right angle thereto.

5. In combination, a fixed support having 55 an opening therethrough, a bearing member rotatable in the opening, a lever like mem-

ber, laterally projecting trunnions on the lever and journaled upon the said rotatable member, one end of the lever like member extending beyond the said bearing member 70 and forming a handle on one side of the said support, the other end of the lever like member extending to the other side of the support and shaped to assume a position in close proximity to and in a plane substantially parallel with the adjacent face of the support, a spot light connected with the last recited end of the lever like member and at a substantially right angle thereto, and means for increasing the friction between 75 the said trunnions and their bearings upon the said rotatable member.

6. In combination, a fixed support having an opening therethrough, a pair of opposed bearing members rotatable in the opening, a lever like member passing through the said bearing members and shaped to form a handle on one side of the fixed support, a lamp casing connected with the other end of the lever, the axis of the casing being transverse 80 to the length of the lever and offset sideways with respect to the center of the pivot of the lever and toward the fixed support, means pivotally connecting the lever intermediate its ends with the said bearing members, and annular members encompassing the 85 said lever like member and engaging opposite faces of the said fixed support and the bearing members for maintaining the latter in position.

7. In combination, a fixed support having 90 an opening therethrough, a pair of opposed bearing members rotatable in the opening, a lever like member passing through the said bearing members and shaped to form a handle on one side of the fixed support and a lamp support on the other side of the fixed support, a lamp casing connected with the last said end of the lever and at a substantially right angle thereto, means pivotally connecting the lever intermediate its 95 ends with the said bearing members, and annular members encompassing the said lever like member and engaging opposite faces of the said fixed support and the bearing members for maintaining the latter in position, the lamp supporting end of the said lever like member being shaped to assume a position in close proximity to and substantially parallel with the adjacent face 100 of the said fixed support.

8. In combination, a fixed support having 105 an opening therethrough, a pair of opposed bearing members rotatable in the opening, a lever like member extending through said members and shaped to form a handle on one side of the fixed support and a lamp support on the other side thereof, a lamp casing connected with the lever at a substantially right angle thereto, the lamp supporting end of the lever being shaped to as- 110 115 120 125 130

- sume a position in close proximity to the adjacent face of the fixed support and substantially parallel thereto, trunnions on the lever and journaled between the said bearing members, and annular members encompassing the said lever and engaging opposite faces of the fixed support and the said bearing members for holding the latter in position.
10. 9. In combination, a fixed support having an opening therethrough, a pair of opposed bearing members rotatable in the opening, a lever like member extending through said members and shaped to form a handle on one side of the fixed support and a lamp casing support on the other side thereof, a lamp connected with the lever at a substantially right angle thereto, the lamp supporting end of the lever being shaped to assume a position in close proximity to the adjacent face of the fixed support and substantially parallel thereto, trunnions on the lever and journaled between the said bearing members, annular members encompassing the said lever and engaging opposite faces of the fixed support and the said bearing members for holding the latter in position, and means for varying at will the friction between the said bearing members and the said trunnions.
10. In combination with a vehicle windshield having an opening therethrough, a bearing mounted within the opening to turn therein, a lever like member passing through the opening and connected with the bearing for movement on an axis transverse to the axis of rotation of the bearing, and a spotlight on one side of the windshield and con-

nected with one end of the lever like member so that the center of the light will be offset with respect to the center of the pivot of the said lever like member in any position into which the said lever may be moved, said end of the lever adapted to assume a position in a plane substantially parallel with the face of the wind shield, the other end of the said lever like member being shaped to form a handle on the other side of the windshield.

11. In combination with a vehicle windshield having an opening therethrough, a bearing mounted within the opening to turn therein, a lever like member passing through the opening and mounted upon the bearing for movement on an axis transverse to the axis of rotation of the bearing, and a light casing on one side of the windshield and connected with one end of the lever like member so that the center of the light casing will always be offset with respect to the center of the pivot of the said lever like member, the other end of the said lever like member being shaped to form a handle on the other side of the windshield, the said lever like member being so shaped that the transverse axis of the light casing is adapted to assume a position in a plane substantially parallel with the face of the windshield to bring the said casing in close proximity to the said face of the windshield.

In testimony whereof we have signed our names to this specification, on this 8th day of March, A. D. 1923.

GUSTAF E. KRANTZ.
CARL A. KRANTZ.
